DEVICE FOR REPRODUCTION OF INSTANTANEOUS OCCURRENCES

Werner Flechsig, Berlin-Charlottenburg, Germany, assignor to the firm of Fernseh Aktien-Gesellschaft, Zehlendorf, near Berlin, Germany

Application August 14, 1937, Serial No. 159,185
In Germany September 22, 1936

5 Claims. (Cl. 250—150)

This invention relates to the permanent or fleeting visible reproduction of transient occurrences. It is frequently desirable to observe oscilograms of transient effects during a relatively long time, or to record visibly a single phase of a rapid motion of an object for a longer period immediately after the motion is made, or finally, to extend the instantaneous effect of a television picture signal for one picture element over a period of time in the order of the frame period, for the purposes of television transmission or reception.

It is the object of the present invention to provide a new and improved recording and transmitting means.

It is a known fact that a metal plate which is covered by a thin insulating layer, provided with a coating of electro-positive material, emits electrons over a long period after an excitation by an electron bombardment has ceased. This has been proven with an aluminum plate electrolytically oxidized and treated with caesium. This phenomenon is explained by the creation of strong electrostatic fields in the thin insulating layer.

According to the present invention there is provided an envelope containing such a thin film cold emission plate adapted to be impacted by an exciting electron beam produced by an electron gun within the same envelope. The cold emission from the plate is focused in image relation upon an image screen, for example a fluorescent screen, by means of an electron optical system. Such an arrangement makes it possible to render a single transient occurrence visible over a longer period of time. A device of this type is also suitable as a receiver for television images if the plate is prepared in such a manner that the cold emission decays during the period of one television picture frame.

It has been found that it is possible to influence the cold emission by illumination. This phenomenon may either be used to terminate the cold emission, or it may be used for the development of negative images in a manner which will be described below. Heating of the plate to a sufficiently high temperature can also be used to terminate the cold emission. The advantage of this arrangement over known receiver tubes is that the luminescent picture screen is exposed to electron bombardment during almost the entire time of the operation of the tube so that it may be put under heavier load than in the usual method of operation where it receives a bombardment lasting only 1 microsecond and which is, therefore, very intensive.

A further application lies in the field of so-called image translators. An image produced by exposing a photocathode for a short time to the light of an optical image can be held on a fluorescent screen over a period of hours. A further possibility of application is to pre-excite the plate by uniform bombardment with cathode rays while a localized neutralization of varying degree of the excited state takes place by means of a different kind of ray, as for instance light; ionic, or X-rays.

The accompanying drawing shows several preferred embodiments of the invention. Figs. 1 and 2 both show an image receiver tube, Fig. 3 shows an image translator and Fig. 4 shows an image transmitting tube.

In Fig. 1 the tube 1 contains an electron gun 2 of a conventional construction. The cathode ray produced by the electron gun is sharply focused by means of a focusing lens 3 and is deflected over the area of a composite plate 6 by means of the deflecting systems 4 and 5. The plate 6 consists of a thin aluminum layer, the surface of which is electrolytically oxidized. The oxide layer is indicated by the dotted line 7. Furthermore, the oxide layer is treated with an electro-positive material, for example caesium, which is indicated by the waved line 8. The tube also contains a fluorescent screen 9 which is disposed opposite to the plate 6. The cold emission emitted by the plate is focused upon the fluorescent screen 9 by means of an electron optical lens 10 which is preferably a long coil. According to Fig. 1 the bombardment of the plate occurs on the same side of the plate 6 from which the cold emission is emitted. In Fig. 2 the aluminum portion of the composite plate 6 is made so thin that it is permeable for the exciting bombardment impacting this side of the plate. The cold emission, however, occurs on the other side, wherefore that the plate is disposed between the electron gun and a fluorescent screen 9. In order to terminate the cold emission during the television picture retrace time for moving pictures the plate is either exposed to light for a very short time between two pictures, or the light generated by the fluorescent screen is partly allowed to fall back upon the plate so that the cold emission is made to decay, by virtue of the illumination generated by it, within a desired time interval. For this purpose it is also possible to heat the plate either by resistance or induction heat.

The image translator of Fig. 3 contains a photocathode 11, a composite plate 6 with the layers 7 and 8, and a fluorescent screen 9. An electron optical system 12 serves to focus the emission of the photocathode 11 upon the plate 55

6 and to focus the cold emission upon the fluorescent screen 9. The plate 6 is held at a potential intermediate those of the photocathode and the fluorescent screen. The plate is preferably 5 made in such a manner that it is permeable for the exciting photoelectrons but still not translucent. On one side of the photocathode 11 there is a dark chamber 13 with an optical objective 14 and a shutter 15, as is common in photographic cameras. If the photocathode is exposed 10 to the light of an optical image for a short time by operating the shutter, the plate 6 is excited to produce cold emission and an image is generated upon the fluorescent screen 9, which stays just 15 as long as the cold emission lasts. Optical regeneration does not take place because the plate 6 is not transparent. In order to prevent the light from the fluorescent screen 9 from terminating 20 the cold emission prior to the desired instant, it is advisable to use a luminescent material, the light of which embraces such a spectral range that the cold emission is not influenced thereby.

In a modified arrangement the photocathode 25 is also provided with fluorescent properties and the electron optical system can be reversed by a change of potentials. In this case the optical image is projected upon the photocathode for a short time and the photoemission is focused upon 30 the composite plate. The potentials are then changed so that the element previously functioning as the cathode now functions as the anode and the cold emission is focused by the electron optical system upon the photoelectric 35 surface from which the photoelectrons were emitted, and there produces a visible image, due to the fact that this surface is also fluorescent.

The television picture signal transmitting tube shown in Fig. 4 contains an electron source 16, 40 for example a thermionic cathode, the emission from which uniformly floods the composite plate 6. The cold emission is then uniform over the entire area of the plate 6. By exposing the side of the plate 6 facing the optical system 17 to 45 light, the cold emission is locally decreased to varying degrees in accordance with the light intensity of the corresponding picture elements and the plate 6 emits only from those spots upon

which no or very little light has fallen. The emission from the plate 6 is then focused in the plane of the stationary target 18 and is deflected across this target by means of the deflecting systems 19 and 20, so that a picture signal can 5 be taken from the signal lead 21 of the target.

I claim:

1. A cathode ray device comprising an evacuated envelope containing an electron gun and a fluorescent plate, a cold cathode positioned to 10 receive electrons from said gun and to direct emission to said fluorescent plate, said cold cathode comprising a conducting plate having a thin nonconducting surface on the side thereof disposed toward said electron gun, and having a 15 secondarily emissive layer disposed on said thin nonconducting surface.

2. A cathode ray device comprising an evacuated envelope having therein an electron gun and a fluorescent plate, a cold cathode disposed 20 between said gun and said fluorescent plate comprising a thin conductive layer permeable to electrons from said gun, an insulating layer disposed upon the side of said conductive layer away from said gun, and a secondarily emissive layer disposed on said insulating layer on the side thereof 25 away from said electron gun.

3. A cathode ray device substantially as described in claim 1 having electron focusing means disposed about said envelope between said cold 30 cathode and said fluorescent plate.

4. A cathode ray device substantially as described in claim 1 having electron focusing means disposed about said envelope between said cold cathode and said fluorescent screen, and having 35 means for polarizing said cold cathode.

5. A cathode ray device comprising an envelope containing an electron gun and a plate capable of luminescing in response to bombardment by electrons, a cathode positioned to receive electrons from said gun and to direct emission to said plate, said cathode comprising a conducting plate having a thin non-conducting surface on one side thereof and having secondarily emissive material disposed on said thin non-conducting 40 surface.

WERNER FLECHSIG.
